Patented Feb. 28, 1922.

UNITED STATES PATENT OFFICE.

JOHN HARRIS, OF LAKewood, OHIO.

BLOWPIPE.

1,408,194.

Specification of Letters Patent. Patented Feb. 28, 1922.

Application filed March 29, 1918. Serial No. 225,431.

To all whom it may concern:

Be it known that I, JOHN HARRIS, a citizen of the United States, residing at Lakewood, in the county of Cuyahoga and State of Ohio, have invented a certain new and useful Improvement in Blowpipes, of which the following is a full, clear, and exact description, reference being had to the accompanying drawings.

This invention relates to blowpipes such as are employed in the arts of cutting and welding with gases. It is the general object of my invention to provide a blowpipe which is particularly efficient in operation. More limited objects of the invention are to provide a blowpipe having a construction and arrangement of passageways whereby, by a mere variation in the cross-sectional areas of such passageways, the same style of pipe may be used for all of the commercial gases and vapors; to provide a blowpipe which will not only burn all of such gases and vapors, but one wherein the flame will not blow out under such variations of pressure as are employed in cutting different thicknesses of metal; also to provide a blowpipe wherein back-firing in the high pressure oxygen passageway will be prevented; to provide a blowpipe wherein the preheating operation may be accomplished more quickly and with a smaller gas consumption than is possible with any other form of pipe with which I am familiar; to provide a blowpipe the tip orifices whereof are readily and conveniently cleaned without the necessity for disassembling; to provide a blowpipe wherein a supply of cutting oxygen, ample in quantity and uniform in pressure, will be secured at all times, with no restriction such as exists in the ordinary type of drilled or bored-head pipes; to provide for such pipes a new and efficient arrangement of the oxygen injector for the preheating jets or orifices; and to provide a novel construction of valve for the cutting oxygen. I secure these results and advantages in and through the embodiment of my invention illustrated in the drawings forming part hereof, wherein Fig. 1 represents a side elevation of such blowpipe; Fig. 2 an enlarged central vertical sectional view through the blowpipe head and tip and the adjacent ends of the pipes conveying the various gases thereto; Fig. 3 a sectional view corresponding to the line 3—3 of Fig. 2; Fig. 4 a sectional view corresponding to the line 4—4 of Fig. 1; Fig. 5

a sectional view corresponding to the line 5—5 of Fig. 4; Fig. 6 a side elevation of the inner member of the tip; Figs. 7 and 8 sectional views corresponding respectively to the lines 7—7 and 8—8 of Fig. 2; and Fig. 9 a detail in perspective of the washer inserted between the inner tip member and the head.

Describing by reference characters the various parts illustrated herein, 1 denotes a cylindrical shell constituting a handle for the blowpipe and through which shell there extend the pipes 2, 3, and 4, said pipes communicating at their rear ends with passageways in a casting 5 to which the rear end of the sleeve 1 is secured, as by means of a screw 6. Projecting from the rear end of the casting 5 are the connections 7 and 8, the former connection receiving oxygen and the latter connection a combustible gas or vapor. The flow of oxygen through appropriate passageways in the casting 5 (not shown) to the tubes 2 and 3 is controlled by a valve 9 while the flow of combustible gas from the connection 8 and the casting 5 passageway (not shown) to the tube 4 is controlled by the valve 10.

The pipe 2 conducts oxygen for cutting purposes to a blowpipe head and is provided with a valve, which will now be described. This valve comprises generally a casing 11 having a rearwardly extending connection 12 for one of the branches of the tube 2 and a forwardly extending connection 13 for the other branch of said tube. The casing is preferably formed as a casting having a head provided with a central bore 14 in which there is reciprocably mounted a valve-operating stem 15, the inner portion of said stem being reduced to provide an annular passageway therearound within said bore. The outer end of the stem passes through a suitable stuffing box 16 and is adapted to be engaged by a lever 17 pivoted between a pair of forks 18 (as indicated at 19) extending forwardly from the head. The rear end of the lever 17 projects beyond the front end of the handle 1, in convenient position to be grasped by the operator when it is desired to open the valve controlling the supply of cutting oxygen. The inner end of the bore 14 communicates with a cylindrical chamber 20 within the casing 11, there being an outwardly projecting annular valve seat 21 surrounding the inner end of said bore. The valve is mounted within the chamber 20 and comprises a body 22, prefer-

ably of brass and hexagonal in shape, said body having at one end thereof an annular recess in which there is pressed a rubber valve 23, this valve being held within the recess by pressing inwardly the outer wall surrounding the same, as indicated at 21^a. The end of the casing 11 which is opposite the lever 17 is provided with a cap 24 threaded thereupon, and between said cap 10 and the valve body 22 a helical spring 25 is interposed, said spring normally holding the valve to its seat.

The rear branch of the oxygen pipe 2 communicates with the chamber 20 by means of 15 an inclined passageway 26 while the front or forward branch of said pipe communicates with the bore 14 by an inclined passageway 27.

At their front ends, the pipes 2, 3 and 4 20 are connected to the rear of the blowpipe head 28 and communicate respectively with a chamber 29 and passageways 30 and 31 in said head. The chamber 29 is cored and branched, the front ends of the branches 25 merging, as shown at 29^a, above the central head passageway 32 for the cutting oxygen. Between the branches of the chamber 29 the head is drilled, as indicated at 33, to provide a chambered passageway extending nearly 30 in the same direction as the central oxygen passageway 32 and forming only a slight angle therewith. The upper portion of the passageway 33 is threaded for the accommodation 35 of the injector by which the preheating oxygen is enabled to inject and form a pre-heating mixture with the combustible gas supplied through the pipe 4 and passageway 31. The injector is formed as part of the plug 34, the lower end whereof is enlarged 40 and threaded to engage the thread within the chambered passageway 33, as indicated at 34^a. The lower end of the plug is provided with a central bore or passageway 35 communicating by cross ports 35^a with the 45 annular space provided between the reduced portion of the plug and the interior of the chambered passageway 33 above said head and with which annular space or chamber the passageway 30 communicates. The upper end of the injector plug is provided 50 with a head 34^b, between which and the adjacent surface of the blowpipe there is inserted a suitable packing washer 34^c. The lower end of the head 34^a is tapered, and 55 this tapered end extends across the passageway 31. With this arrangement, preheating oxygen is supplied to the bore 35 through the cross bores or passageways 35^a and serves to inject the combustible gas supplied 60 through pipe 4 and passageway 31 and to form an intimate mixture therewith during the flow of such gases through the passageway 36 (forming an axial continuation of the passageway 33) through the annular

chamber 37 in the blowpipe head and the passageways provided between the tip members. 65

The chamber 37 extends upwardly from the lower end of the head 28 and merges with a reduced internally threaded chamber the upper end of which in turn merges with 70 the passageway 32. This internally threaded chamber receives the upper end of the inner tip member 38 which is threaded thereinto, as indicated at 38^a.

The tip as a whole comprises an inner 75 member 38 and an outer member, to be referred to hereinafter. The inner member comprises a plug having a central axial bore 39 of the same diameter (throughout the major portion of its extent) as and 80 adapted to register with the passageway 32. At its lower end, the bore 39 is reduced to provide a restricted discharge passageway 39^a, the wall of the bore 39 being tapered, as indicated at 39^b, to facilitate the even 85 flow of the gas from the larger to the restricted portion of the central bore. The tip plug 38 is provided with a cylindrical upper enlargement 40 and below the lower end of such enlargement with a short cylindrical enlargement 41 merging at its lower end with a frusto-conical surface 42. The portions 40, 41 and 42 are adapted to fit snugly within the outer tip member, as will be explained hereinafter. These projections 95 or enlargements provide means for centering the inner tip member within the outer tip member and also means whereby passageways may be provided for the mixture of preheating gases conducted to the delivery 100 end of the pipe.

40^a denotes slots, preferably V-shaped or triangular in cross-section, which extend radially inwardly from the outer wall of the projection 40 and which serve to conduct the mixture of gases within the chamber 37 to a series of V-shaped or triangular slots 41^a and 42^a extending radially inwardly from the outer surfaces of the tip portions 41 and 42 and providing passageways for the 110 preheating gases. Three such slots 40^a are shown, and their aggregate cross-sectional area is such as to conduct the gases freely from the chamber 37 to the slots 41^a and 42^a. The slots 42^a are formed as continuations 115 of the slots 41^a and, as shown particularly in Fig. 8, extend inwardly as nearly as possible to the central bore of the inner tip member, the bottoms of the slots 41^a being parallel with the said bore while the bottoms 120 of the slots 42^a are inclined towards said bore at a slightly less angle than the outer sides thereof. The bottoms of the slots 42^a are not exactly parallel with the outer surface 41^a but are inclined toward such outer 125 surface to an extent aggregating about 3/1000 inch in a distance of about 1-1/4 inch, the bottoms of the slots being about

1/100 inch from the discharge end of the central bore—regardless of the size of the tips, the diameter of the central bore, and the size of the slots 42^a.

5 Cooperating with the inner tip member is the outer member 43, said member having a cylindrical upper end adapted to be slipped within the lower end of the chamber 37 and having a lower frusto-conical end 43^a. The 10 inner cylindrical and frusto-conical walls of the outer tip member are adapted to form a close fit with the portions 40, 41 and 42 of the inner member; and the outer and inner tip members are usually fastened in operative 15 relation to each other, as by means of a pin (not shown). A leak-proof joint is provided between the outer tip member and the bottom of the head 28 by means of a packing washer 44 within a gland nut 45 which 20 is threaded onto the lower end of said head.

I have found that, by inclining the surface 42 at an angle of about 4-1/2° to the axis or bore of said inner member and by forming the passageways 42^a in the manner 25 shown and described, I am enabled to obtain very important advantages in operation. For instance, I am enabled to impinge the ignited preheating gases more nearly upon a single spot of metal (in the line of the 30 axis of the tip) than is possible with any other form of blowpipe with which I am familiar; this results in a more nearly instantaneous preheating of the metal with a minimum consumption of gas. The particular 35 shape of the slots contributes to this result. Moreover this particular shape of the slots 42^a enables me to bring the inner edges or bottoms thereof in the closest possible proximity to the central bore without 40 weakening the tip so as to render it incapable of withstanding the incidents of use.

In what is known to the trade as a "No. 1" tip, the diameter of the central bore 39^a is the same as that of a No. 56 drill. Six slots 45 42^a are shown, and the area of the discharge end of each of said slots varies as follows, with the same diameter of central bore, with the use of different gases:—

with acetylene, 25/1000 square inch; 50 with "carbo-hydrogen", 35/1000 square inch; with hydrogen, 41/1000 square inch; with artificial gas, 42/1000 square inch; with natural gas, 45/1000 square inch; with thermalene, 45/1000 square inch.

55 These dimensions will insure the production of a maximum size preheating flame for the particular size of cutting jet or orifice specified. In tips of greater capacity, it will be necessary only to preserve the same 60 ratio between the areas of the slots and that of the central bore for oxygen. The particular shape of the slots 42^a (increasing in cross-section from the bottom to the top) prevents dirt or sediment from becoming 65 jammed in said slots and enables the tip to be

cleaned by means of wires inserted through the lower ends thereof.

So far as I am advised, the tip shown and described herein is the only style of tip or blowpipe that will burn all of the gases 70 above specified and such gases as casing gas, rock gas, gasolene vapor, alcohol vapor, and, generally, all of the commercial gases by a mere variation in the cross-sectional area of the slots 41^a, 42^a. Because of the particular taper of the lower end of the inner member or plug and the consequent taper or inclination given to the slots 42^a, the tip will burn all of the above mentioned gases and 75 will do so without the blowing out of the 80 flame under the range of pressures ordinarily employed in cutting different thicknesses of metal.

By the particular arrangement of injector (extending as nearly as practicable in the 85 same direction as the preheating passageways and the central duct for high pressure oxygen) a maximum efficiency is secured in the mixing of the preheating gases and in their delivery to the slotted passageways 90 of the tip.

The manner of forming the chambered oxygen passageway 29 in the head provides therein a large high pressure oxygen chamber which secures an ample supply of such oxygen to the central bore of the tip and an even pressure within such bore; there is no 95 restriction of the oxygen supply such as exists in blowpipes wherein this gas is supplied through a drilled or bored passageway. 100

The high pressure oxygen valve described herein is particularly efficient in operation. The hexagonal or angular shape of the body 22 enables the oxygen freely to enter the chamber 20; the rubber valve body 23 can^a 105 not mar or injure the narrow annular seat 21. The oxygen, being supplied to the chamber 20, assists normally in holding the valve body 22 to its seat, enabling me to use a light tension spring 25, which makes it extremely 110 easy to unseat the valve by the operation of the handle of the lever 17. Furthermore, the valve body 22 is extremely cheap of production and, when the rubber valve portion thereof becomes worn, it may be conveniently 115 removed and replaced with a new one at the place of use and at a trifling expense.

The great majority of all back fires which occur within blowpipes is due to the leakage between the tip and the head into the 120 high-pressure connection. As blowpipes are usually constructed, the duct for high pressure oxygen therein is formed jointly of passageways or bores in the head and in the tip. After the pipe becomes heated through 125 operation, there is an unequal expansion of the metal in the head and that in the tip, resulting in a separation or breaking of the joint between the head and the tip which allows the preheating gases and the high 130

pressure oxygen to form an explosive mixture in the high pressure oxygen passageway. I have been able to obviate this leakage entirely by means of a washer 46 consisting of a thin outer annular shell of copper containing asbestos, as indicated in Fig. 9, the central bore 46^a of said washer registering with and forming with the passageway 32 and bore 39 a duct for the high pressure oxygen. This washer, by its capability of expansion after compression by the upper end of the plug 38, effectually takes care of the unequal expansion between the head and the tip after the blowpipe becomes heated, maintains a closed joint between the head and the tip, and thus prevents the leakage of preheating gases into the high pressure oxygen duct.

To secure the best results the walls of each of the slots 42^a form an angle of about 60° with each other. The opposite walls of each web (intermediate adjacent slots) are substantially parallel; and the bottom or inner walls of the slots can be brought into extremely close proximity to the central bore by this arrangement.

Having thus described my invention, what I claim is:—

1. In a blowpipe, the combination of a head, and a tip connected thereto, said tip having a central bore for cutting oxygen and having a plurality of V-shaped passageways for preheating gases grouped about and converging toward the delivery end of said bore at an angle of approximately four and one-half degrees.

2. In a blowpipe, the combination of a head, and a tip connected thereto, said tip having a central bore therethrough and having a plurality of V-shaped passageways for preheating gases grouped about said bore and converging toward the delivery end of said bore at an angle of approximately 4-1/2°, the upper ends of said passageways being deeper than the lower ends thereof and the lower ends of said passageways being approximately 1/100 inch from said bore.

3. In a blowpipe, the combination of a head, and a tip detachably connected thereto, said tip comprising an inner member having a central bore, the lower or discharge end of said inner member being tapered towards said central bore at an angle of approximately four and one-half degrees and provided in such tapered portion with inwardly extending V-shaped slots and an outer member surrounding the inner member and having its lower end tapered to conform to the tapered end of the inner member and to provide therewith an outer wall for each of said slots, the delivery ends of said slots being approximately 1/100 inch from the delivery end of said bore.

4. In a blowpipe, the combination of a head, and a tip detachably connected thereto,

said tip comprising an inner member having a central bore therethrough and having its lower end tapered toward said central bore at an angle of approximately four and one-half degrees, such tapered lower end being provided with V-shaped slots extending inwardly from the outer surface toward said bore, the upper ends of said slots being deeper than the lower ends thereof and the lower ends of said slots being approximately 1/100 inch from said bore, and an outer member surrounding the inner member and having a tapered lower end conforming to the tapered lower portion of the inner member and forming therewith an outer wall for the slots thereof.

5. In a blowpipe, the combination, with a head having a longitudinally extending passageway therein, of an injector in said passageway, said injector having a central oxygen bore at the lower portion thereof, there being a passageway for conducting a combustible gas to the first mentioned passageway adjacent to the delivery end of said injector, said head having a chamber for cutting oxygen extending about the said injector, and a tip having a central bore arranged to receive cutting oxygen from said chamber and provided with passageways for the preheating gases conducted through the first mentioned passageway.

6. In a blowpipe, the combination, with a head having a chamber for preheating gases and provided with a longitudinally extending passageway communicating therewith, of an injector in said passageway, said injector having a central bore at the lower portion thereof for oxygen, there being a passageway for conducting a combustible gas to the first mentioned passageway adjacent the delivery end of said injector, said head having a duct for cutting oxygen, and a tip having a central bore arranged to receive cutting oxygen from said duct and provided with passageways for the preheating gases conducted through the first mentioned passageway.

7. In a blowpipe, the combination of a head having a branched chamber for cutting oxygen, and a tip having a central bore for such cutting oxygen and passageways for preheating gases surrounding said bore, said head having a passageway extending through said chamber and approximately in the direction of said preheating passageways and said bore and also having passageways for preheating oxygen and combustible gas communicating with the first mentioned passageway, and an injector in said first mentioned passageway arranged to conduct preheating oxygen in operative relation to the delivery end of the passageway for combustible gas.

8. A valve for cutting blowpipes comprising a cylindrical chamber and means for

conducting fluid thereto, an angular valve body in said chamber and having at one end thereof a valve of compressible material, an outlet passageway extending from said 5 chamber, an annular valve seat surrounding said passageway and adapted to engage said valve, an inlet passageway communicating with said chamber, a stem in said outlet passageway for unseating said valve, and a 10 spring in said chamber tending to hold the valve on its seat.

9. A valve for blowpipes comprising an angular metal body having an annular recess in one end thereof, and rubber in said 15 recess, the metal wall surrounding said recess being pressed inwardly to retain the rubber within said recess.

10. In a blowpipe, the combination of a

head, and a tip connected thereto, said tip comprising an inner member having a central bore for cutting oxygen and a plurality of V-shaped slots grouped about said central bore and extending inwardly from the outer wall of said member and converging toward the delivery end of the said bore at an angle 20 of approximately $4\frac{1}{2}^{\circ}$ with said bore and having their delivery ends in close proximity to the delivery end of said bore, the walls of each slot forming with each other an angle of substantially 60° , and an outer 25 tip member surrounding the delivery portion of the inner tip member and closing the outer sides of said slots.

In testimony whereof, I hereunto affix my signature.

JOHN HARRIS.
